CLAIM

The ornamental design for a combined kayak motor and motor mounting apparatus, as shown and described.

DESCRIPTION

FIG. 1 is a top left front perspective view of a combined kayak motor and motor mounting apparatus showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left elevational view thereof;

FIG. 7 is a reduced left elevational view showing an alternate position for the combined kayak motor and motor mounting apparatus; and,

FIG. 8 is a reduced left elevational view showing a further alternate position for the combined kayak motor and motor mounting apparatus.

The broken line showing a kayak or watercraft is included for the purpose of illustrating environmental structure and forms no part of the claimed design.

1 Claim, 8 Drawing Sheets
